(57) **CLAIM**

The ornamental design for a makeup lamp, as shown and described.

DESCRIPTION

FIG. 1 is a top, front, and right side perspective view of a makeup lamp, showing my new design.

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labeled 9 in FIG. 1.

FIG. 10 is an enlarged view of a portion labeled 10 in FIG. 2;

FIG. 11 is an enlarged view of a portion labeled 11 in FIG. 5;

FIG. 12 is an enlarged view of a portion labeled 12 in FIG. 5; and,

FIG. 13 is an enlarged view of a portion labeled 13 in FIG. 7.

The dash dot lines in FIGS. 1, 2, 5, 7, 9-13 are for the purpose of depicting the boundary of the enlarged view and form no part of the claim.
